[57] CLAIM

The ornamental design for a diskette case make up and cosmetics holder, as shown and described.

DESCRIPTION

FIG. 1 is a side view of the first embodiment of the diskette case make up and cosmetics holder showing my new design; FIG. 2 is a top view of the first embodiment of the diskette case make up and cosmetics holder having rectangular shaped make up holding areas;

FIG. 3 is a side view of the second embodiment of the diskette case make up and cosmetics holder showing my new design; and,

FIG. 4 is a top view of the second embodiment of the diskette case make up and cosmetics holder having circular shaped make up holding areas.

The surface(s) or portion(s) of the article not shown in the drawing or described in the specification form(s) no part of the claimed design.
